Attorney.

UNITED STATES PATENT OFFICE.

MYRTLE LORRAINE BRATT, OF CINCINNATI, OHIO.

EXTENSION FOOT FOR LADDERS.

Application filed June 30, 1927. Serial No. 202,690.

This invention relates to auxiliary extensible-devices for use at the lower ends of step-ladders, fire-ladders and other types of service-ladders used on floors or other foundation or resting surfaces that are in any wise uneven and subject the ladder to wobble or to unduly lean to one side to the discomfort and bodily risk of the user as well as toppling over with its load, and thus liable to 10 result in greater or less damage to its load and to surrounding adjacent objects.

The object of my present improvement is to provide a very simple and economical form of compensating-device which is composed of 15 a strip or length of channel-iron that is adapted to be readily telescoped into acting-place on one of the lower ends of the ladder to take up or fill in the space between the said lower end and the uneven footing below and 20 thereby prevent wobbling or toppling of the ladder on account of such unevenness, the said channel-iron being itself provided with a pivotal cast-off clamp that is eccentrically-mounted in a pair of lateral ears that project 25 from the opposite flaring side-walls of said channel-iron between its opposite ends and thereby adapted to take firm grip-hold on the lower end of the ladder that is to be rectified in height above the said uneven footing, 30 all of which will be clearly and fully described in connection with the accompanying sheet of drawings, in which—

Figure 1 is a front-face perspective view of my channel-iron and eccentric-clamp structure embodying the invention herein, the said eccentric-clamp being shown thrown downward into disengaging-position and omitting the ladder, but otherwise ready for telescopic-attachment or in using-place at the 40 foot of the ladder-member needing the compensating-extension for any uneven footing below; Fig. 2, a cross-section taken on the horizontal dotted-line 2, 2, of Fig. 1; Fig. 3, a fragmentary perspective view showing the 45 fore-stiles at the lower end of an ordinary step-ladder in use on an offset surface, such as a step, and with one of my improved compensating extension-devices in clamped-place at the bottom of the left fore leg or stile 50 so as to meet the difference in the two levels or unevenness of the footing for the ladder on which it rests for use; Fig. 4, a fragmentary side-elevation of the lower end of the said left-hand stile seen in Fig. 3, but on a 55 somewhat larger scale, and showing an en-

compassing elastic pad or cup on the channel-iron member to cushion the lower end thereof against slipping and injury to the resting-surface below; and Fig. 5, a central vertical section of Fig. 4, looking toward the 60 inner face of the channel-iron but omitting the lower end of the said side-stile.

In applying my device, the lower supporting-ends of the pair of fore-stiles A and B of an ordinary household step-ladder are 65 shown, including the usual lower step C and its under cross-brace D. The said stiles, A and B, are of equal length, (as of course and customary,) and the said step-ladder has the usual back-prop member (not shown) 70 containing a pair of legs whose lower ends are subject to resting on uneven surfaces and adapted to be supplied or armed with the same auxiliary compensating extension-device as the one seen in Fig. 3 (for either of 75 said fore-stiles A and B that requires its extensible or take-up support).

My said auxiliary, compensating extension-device consists of a vertical, main or body-portion 6 which is of channel-iron that has 80 a flat back 7 and a pair of inwardly sloping or flaring side members or jaws 8, 8, duly spaced apart and provided near their upper ends with outwardly-extended or lateral ears 9, 9, to accommodate a pivotal locking-clamp 85 10, all as best seen in Fig. 1. The said locking-clamp 10 is composed of a cam-block or body-portion 11 that has a transversely toothed or corrugated convex or half-round front-face 12 and a working handle or lever 90 13 and is pivotally-mounted on a transverse bolt or pin 14 that bears in the said ears 9, 9, on the side jaws of the channel-iron 6. The bolt 14 passes through a hole in the cam-block 11 eccentric to its convex or rounded front- 95 face 12 so that in operating the clamp in contact with the face of the lower end of one of the side-stiles, or of one of the back prop-legs, its toothed or corrugated face 12 impinges or impresses itself firmly into the surface of 100 the stile or prop-leg, as the case may be, in the leveling or evening of the ladder, proof against slipping or teetering up and down while the said ladder is in use, and especially with a weight or burden of any kind upon it. 105 In Fig. 3, I show how the device may be used on the lower end of the left-hand stile A of a step-ladder which is in use on a stairway or in a position where there are two decidedly uneven surfaces or levels F and G. In this 110

particular instance it will be observed that the lower end or foot of the channel-iron extension 6 rests in contact with the lower level F after the compensating device herein has been adjusted to the desired distance below the extreme lower end of the ladder stile A to correspond to the difference of the said two levels F and G, whereby the ladder has a firm, solid and steady footing or bearing on the said two levels the same as though it were on but a single true level, and without any wabbling or tottering of the ladder being possible on account of said decided difference in levels of the resting-points of the two stiles of the ladder, the same condition being possible and carried out at the lower ends of the rear-prop (not shown), where it rests on the same differing pair of levels also.

The device herein forms a ready cast-off for both adjusting to and from clamping-place on the ladder stiles or on the back-props, and is easily mounted in swinging position intermediate the side ears or bearings 9, 9, by means of the cross-bolt or headed pin 14, which is preferably provided with a cotter-pin 15 for holding it in place.

The bottom of the channel-iron is preferably provided with an elastic cup or pad 16 that is sprung into clinging-place for ready removal, if necessary, and serves to prevent slipping or shifting of the ladder in use on the resting-surface, or injury to such resting-

surface should it be a carpeted or an uncovered costly-finished floor of a building.

It will be easily understood that the device is equally well adapted for use on fire and other service ladders to take the place of the crude make-shift blocks and wedges that have been hurriedly improvised in emergencies on uneven surfaces in streets and on pavements or floors where such service ladders are hastily used or called into use for fires and other dangerous as well as other important needed working service requiring properly sustained upright ladders, or like mounting or climbing apparatus.

I claim:—

A detachable compensating extension foot for an ordinary plane-faced ladder leg, the same comprising an imperforate channel-iron having spaced inwardly-flaring opposite side jaws, a pair of bearing-lugs projecting from the inner edges of the said side jaws, a clamping-member, a transverse bolt pivotally carrying said clamping-member in the said bearing-lugs and having an eccentric serrated cam-face formation for positive and slipless impingement-contact with end of a ladder leg when the device is in operative position, and a hand-lever projecting outwardly from the clamping-member.

In testimony whereof I hereunto affix my signature.

MYRTLE LORRAINE BRATT.
